DEHUMIDIFYING APPARATUS

Frederick O. Anderegg, Newark, Ohio, assignor to
 John B. Pierce Foundation, New York, N. Y., a
 corporation of New York

Application June 26, 1941, Serial No. 399,793

3 Claims. (Cl. 183—2)

This invention relates to dehumidifying means whereby air or other gases are relieved of moisture content.

A primary object of the invention is the provision for rapid, and substantially complete, continuous dehumidification in a simple and inexpensive manner.

Another object is the provision for continuous regeneration of the material used as a dehumidifying agent.

An outstanding novel feature in the accomplishment of the above recited objects, resides in the use of highly pervious, dehumidifying material as a wall between a flow of air, or other gas to be dehumidified, and a flow of heated air, or other gas acting as a regenerative medium. The two flows, in contact with opposite faces of the dehumidifying wall, are preferably in counter directions to enhance the respective actions thereof.

Another feature resides in the provision of cooling means, such as a coil through which water circulates, for absorbing the latent heat of vaporization set free by condensation of the moisture in the air or other gas being dehumidified.

In the drawing:

Fig. 1 represents a vertical section taken centrally through a preferred embodiment of the invention, the midportion being illustrated partly in elevation; and

Fig. 2 represents a horizontal section taken on the line 2—2 of Fig. 1.

Dehumidification pursuant to the invention is advantageously accomplished by the use of a tube of highly pervious dehumidifying material so that a maximum effective dehumidifying surface area is had.

It is preferred that the dehumidifying material employed be that disclosed and claimed in my co-pending application Serial No. 157,136 filed August 3, 1937, and entitled Dehumidifying material, now U. S. Patent No. 2,255,041. Such material may be molded into desired shape in its formative stage. It is extremely porous throughout, and the individual pores thereof intercommunicate so that distribution of absorbed moisture, and passage thereof through the body of the material, is facilitated. Further, the body of the material is rendered chemically hygroscopic by reason of a calcium chlorine constituent.

While the above specified dehumidifying material is particularly advantageous because of its peculiar characteristics, other pervious materials may be successfully used.

In the preferred embodiment illustrated, a tube

10 of highly porous dehumidifying material is set into a cylindrical housing 11, which may be conveniently formed from sheet metal. The tube 10 extends longitudinally through the housing 11, passing through aligned receiving apertures preferably formed centrally of opposite end plates 12 and 13 of the housing. Flange collars 12a and 13a may be struck from the respective end plates, circumferentially of the respective receiving apertures, for anchoring the tube 10 in position.

The housing 11 forms a chamber 14 completely surrounding the greater portion of the length of the tube 10. Through this chamber the air or other gas to be dehumidified is passed. For this purpose, a supply conduit 15 leads into the top of the housing 11 through a suitable receiving aperture provided in the upper end plate 12 to one side of the aperture through which the tube 10 extends. The supply conduit 15 is connected to the source of the air or other gas to be dehumidified (not shown), and, if found desirable in any particular instance, a conventional type of blower may be utilized to induce a positive flow through such supply conduit toward the chamber 14.

A discharge conduit 16 leads from the bottom of the housing 11 through a suitable receiving aperture provided in the lower end plate 13, preferably at a side of the housing 11 which is opposite that into which the supply conduit 15 directly leads.

Heated, relatively dry air or other gas is passed upwardly through the tube 10. For supplying the same, a gas burner 17 may be disposed at the lower end of the tube 10 so that air heated thereby will pass upwardly through the hollow interior of tube 10, as in a chimney. The heated, relatively dry air or other gas may be supplied in any other suitable manner, however, as for instance by connecting a conduit, leading from any suitable source of the heated, relatively dry air or other gas, to the bottom end of the tube 10. The spent heated air or other gas may pass freely out of the top of the tube 10 after traversing the length thereof, or, if desired, discharge piping (not shown) may be connected to the upper end of the tube 10.

Air or other gas to be dehumidified is supplied to the interior of the casing 11 through the supply conduit 15, and is withdrawn therefrom through discharge conduit 16. In its consequent downward flow through the chamber 14, such air or other gas to be dehumidified passes over the outside wall surface of the dehumidifying tube 10, in intimate contact therewith, and gives up

its moisture content to that wall surface. The heated air or other gas flows upwardly within the tube 10, passing over the inside wall surface of the dehumidifying tube 10, and by reason of its dry character, vaporizes and carries off moisture from such inside wall surface. Because the entire body of the wall of tube 10 is pervious to moisture, the flow of heated air or other gas continuously and effectively regenerates the dehumidifying outer surface of the wall of tube 10.

Means for absorbing the latent heat of vaporization released adjacent the dehumidifying outer walls of the tube 10, may be provided in the form of a coiled pipe 18, advantageously of copper, and forming a component part of a circulation system of any desired type (not shown) whereby water, or other cooling fluid, is circulated continuously through the piping.

The specifically illustrated and described embodiment represents a very advantageous practical utilization of the generic concepts of the invention. It should be realized, however, that many changes may be made in such embodiment and many other embodiments may be made by those skilled in the art without departing from the spirit and purview of the invention as set forth herein and in the following claims.

I claim:

1. Dehumidifying apparatus comprising a hygroscopic, pervious wall; a fluid flow channel defined along one face of said pervious wall; a fluid flow channel defined along the opposite face of said pervious wall; a gas inlet to and a gas outlet from opposite ends of one of said channels; a gas inlet to and a gas outlet from opposite ends

5 of the other of said channels; a source of heated gas in communication with said last named inlet; and a heat transfer element disposed in contact with the face of said wall open to the first named channel to remove the latent heat of condensation.

10 2. Dehumidifying apparatus comprising a relatively long pervious tube of dehumidifying material; means forming an enclosed chamber about substantially the length of said tube; an inlet and an outlet for passing air, or other gas to be dehumidified, through said chamber and in intimate contact with the outside face of said tube, an inlet, an outlet, and a source of heated gas 15 in communication with said inlet for passing relatively dry heated gas through said tube in intimate contact with the inside face of said tube; and a cooling element disposed about the outer wall of said tube in heat exchange relationship therewith.

20 3. Dehumidifying means comprising a chamber having an inlet and an outlet; an open-ended tube of pervious water absorptive material disposed within said chamber; an inlet and an outlet for passing air or other gas to be dehumidified through said chamber in intimate contact with the outer surface of said tube over substantially its entire length; a heat source at one end of said tube to cause relatively dry, heated air to flow through said tube; and a cooling coil disposed about the length of said tube within the chamber and in intimate contact with the outer surface of said tube.

FREDERICK O. ANDEREGG.
